Primary Examiner — Jeffrey D Asch*Assistant Examiner* — Caitlin A Laverty(57) **CLAIM**

The ornamental design for a gun cleaning brush kit case, as shown and described.

DESCRIPTION

FIG. 1 is a perspective view of a gun cleaning brush kit case showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in a closed position; and,

FIG. 10 is an enlarged view of portion 10 identified in FIG. 9.

The broken lines throughout the drawing figures depict portions of the gun cleaning brush kit case that form no part of the claimed design.
